RECLINING ARTICLE OF FURNITURE

Anton Lorenz, Buffalo, N. Y.

Application April 19, 1946, Serial No. 663,550

18 Claims. (Cl. 155—106)

1

This is a continuation-in-part of patent application Ser. No. 470,140 filed December 26, 1942.

My invention relates to articles of furniture, and more particularly to a reclining article of furniture, wherein a seat, a back-rest, a top connecting link and a front connecting link are pivotally connected with each other so as to form the sides of a four-sided link-system, and wherein one side of said four-sided link-system is swingably mounted on a support.

In the hitherto known reclining articles of furniture of above described type means are provided for the control of the movements of the sides of the four-sided link-system during the adjustment of the movable members of the reclining article of furniture from one position into another one. It has been found, however, that reclining articles of furniture with a controlled movement of their movable members permit only a limited adjustment of their movable members.

An object of my invention is to provide a reclining article of furniture of above described type, wherein the four-sided link-system may be moved relative to the support without a simultaneous alteration of the position of the sides of the four-sided link-system relative to each other, and wherein the sides of the four-sided link-system may be moved relative to each other without a simultaneous alteration of the position of the top connecting link of the four-sided link-system relative to the support.

A further object of my invention is to provide a reclining article of furniture of above described type having a leg-rest swingably mounted on the seat with means for displacing the leg-rest relative to the seat during a movement of the sides of the four-sided link-system relative to each other.

Still another object of my invention is to provide a reclining article of furniture of above described type having a leg-rest swingably mounted on the seat with means for adjusting the position of the leg-rest relative to the seat.

A further object of my invention is to provide a reclining article of furniture of above described type with a leg-rest swingably mounted on the seat and controlled by a connecting link of the four-sided link-system, which may be brought almost in line with the seat when the latter is in its extreme reclined position, so that the feet of the person resting in the article of furniture are in a level well above the head of the person resting in the article of furniture.

With the above and other objects of the invention in view, the invention consists in the novel

construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining chair according to the invention,

Figs. 2 and 3 are side elevational views of the chair shown in Fig. 1, wherein, however, the movable members thereof are in different positions,

Fig. 4 is a side elevational view of a different embodiment of an adjustable reclining chair according to the invention,

Fig. 5 is a sectional view of a locking device of the chair shown in Fig. 1, taken on line 5—5 of Fig. 1,

Fig. 6 is a side elevational view of a different embodiment of an adjustable reclining chair according to the invention,

Fig. 7 is a perspective view of the support of the adjustable reclining chair shown in Fig. 1,

Fig. 8 is a sectional view of a locking device of the chair shown in Fig. 6, taken on line 8—8 of Fig. 6,

Fig. 9 is a side elevational view of an office chair according to the invention,

Fig. 10 is a fragmentary side elevational view, partly in section, of the office chair shown in Fig. 9, illustrating the latch mechanism of said office chair in an enlarged scale,

Fig. 11 is a sectional view taken on line 11—11 of Fig. 10,

Fig. 12 is a side elevational view of a different embodiment of an adjustable reclining chair according to the invention,

Fig. 13 is a fragmentary front elevational view of the leg-rest, seat, and connecting links of the chair shown in Fig. 12,

Fig. 14 is a perspective view of the support of the chair shown in Fig. 12,

Fig. 15 is a side elevational view of a different embodiment of an adjustable reclining chair according to the invention,

Fig. 16 is an elevational view of the front connecting link of the chair shown in Fig. 15,

Fig. 17 is a sectional view taken on line 17—17 of Fig. 16,

Fig. 18 is a perspective view of a detail of the chair shown in Fig. 15,

Fig. 19 is a sectional view taken on line 19—19 of Fig. 15,

Fig. 20 is a side elevational view of a different embodiment of an adjustable reclining chair according to the invention,

2

Fig. 21 is a sectional view taken on line 21—21 of Fig. 20,

Fig. 22 is a sectional view taken on line 22—22 of Fig. 20, and

Fig. 23 is a side elevational view of the chair shown in Fig. 20, wherein, however, the movable members of the chair are in a different position.

Referring now to Figs. 1, 2, 3, 5, and 7, 20 generally indicates a support made of an integral piece of tubular material bent in suitable manner so as to form a substantially U-shaped ground-engaging portion 22, the legs of which merge into upwardly extending legs 24, one on each side of the chair. The free end 26 of each leg 24 extends toward the rear of the chair and is flattened. Two plates 28 and 30, one on each side of the end 26, are secured to the flattened portion 26 of each leg 24 by means of rivets 32 or the like. Furthermore, each portion 26 has two upper surfaces 34 and 36 arranged at a pre-determined angle with respect to each other for a purpose to be described hereinafter. The legs 24 are connected with each other in their lower portion by means of a reinforcing cross-bar 38.

40 indicates a back-rest pivotally connected to the rear end of a seat 42 at 44. On each side of the chair, the rear end of a top connecting link 52 is pivoted at 56 to an intermediate point of the back-rest 40 above the plane of the seat 42. The front end of each top connecting link 52 is pivoted at 54 to the upper end of a front connecting link 50, the lower portion of which is pivoted to the front portion of the seat 42 at 48. Thus, the seat 42, the back-rest 40, the top connecting link 52 and the front connecting link 50 form a four-sided link-system. In the embodiment shown in Figs. 1, 2 and 3, said four-sided link-system has sides of unequal length.

A leg-rest 46 swingably mounted on the front portion of the seat 42 at 48 is rigidly connected with the front connecting link 50 so as to participate in the movements of the latter. According to the embodiment shown in Figs. 1, 2 and 3, the leg-rest 46 is integral with the front connecting link 50; if desired, however, the leg-rest and the front connecting link could be made of two separate elements rigidly connected with each other by screws or the like.

The top connecting links 52 represent the arm-rests of the chair. The center portion of each top connecting link is placed between the two plates 28 and 30 secured to the end 26 of the leg 24 (see Figs. 1 and 5). A pin 58 having a head 60 for abutting against the plate 30 passes through registering holes 62, 64, 66 of the plates and the top connecting link, so that the four-sided link-system 40, 42, 50, 52 is pivoted to the support 20 at an intermediate point of the top connecting link 52 substantially in the center thereof. The pin 58 prevented from rotation by the engagement of a projecting portion 67 with a corresponding recess of the plates 30 has a threaded end projecting outwardly from the plate 28 and carrying a split washer 68. A locking or clamping screw 70 is screwed on the threaded end of said pin 58 for tightening the screw against the washer 68 so as to press the plates 28 and 30 against the top connecting link 52 and lock the relative position between the top connecting link and the support, if desired. If the screw 70 is not tightened against the washer, the top connecting link 52 may be freely swung about the pin 58. The extreme positions of the top connecting link 52 are limited by the sur-

faces 34 and 36 of the end 26, against which the top connecting link comes to rest.

Likewise, a clamping screw 72 is screwed on the threaded end of the pin 44 forming the joint between the back-rest 40 and the seat 42. If the clamping screw 72 is tightened on the pin 44 prevented from rotation by a projecting portion thereof engaged with a recess of the seat, the adjusted relative position between the members 40, 42, 50 and 52 of the four-sided link-system is locked; if the clamping screw 72 is loosened, the members of the four-sided link-system may be freely moved with respect to each other. The extreme sitting position of the members of the four-sided link-system is limited by the cross-rod 38, against which the leg-rest may abut. The extreme reclined position of the members of the four-sided link-system is determined by the arrangement of these members, i. e. the members of the four-sided link-system may be moved relative to each other, until the leg-rest comes into alignment with the connecting links as shown in dash and dot lines in Fig. 6. When the members of the four-sided link-system are brought into said extreme reclined position, the feet of a person resting in the chair are in a level well above the head of the person resting in the chair.

The chair shown in Figs. 1-3 may be used as follows:

Assume, the four-sided link-system is in the position shown in full lines in Fig. 1, the clamping screw 70 is tightened and the clamping screw 72 is loosened. Under these circumstances the relative position between the top connecting link 52 and the support 20 is locked, the remaining three members of the four-sided link-system, however, may be moved relative to each other. Thus, the user of the chair may swing the back-rest, the seat, the front connecting link, and the leg-rest connected with said front connecting link back and forth by leaning his back against the back-rest or slightly lifting his legs from the leg-rest or by pressing his legs against the leg-rest. Preferably, the pivot 58 is arranged at such a point of the top connecting link, that, in the position shown in full lines in Fig. 1, the load of the user of the chair causes a slight overweight tending to turn the back-rest in clock-wise direction; this overweight may be easily balanced by a slight counter-pressure on the leg-rest. The creation of an overweight facilitates above mentioned swinging movement of three members of the four-sided link-system. The user of the chair may maintain any intermediate position of the members of the four-sided link-system which suits him, for example the position shown in dash and dot lines in Fig. 1, by balancing the movable members of the four-sided link-system by means of a slight pressure on the leg-rest. If desired, however, the user of the chair may lock such an intermediate position of the movable members of the four-sided link-system by tightening the clamping screw 72.

Now assume, the four-sided link-system is in the position shown in full lines in Fig. 1, the clamping screw 70 is loosened and the clamping screw 72 is tightened. Under these circumstances the adjusted position of the members 40, 42, 50, 52 of the four-sided link-system relative to each other is locked, and the user of the chair may use the chair as a swiveling chair swinging about the pivot 58. The extreme positions of the swiveling locked link-system are limited by the surface 34 and 36 respectively of the ends 26,

against which the top connecting link comes to rest. The full line positions of the four-sided link-system shown in Figs. 1 and 2 indicate said two extreme positions.

If desired, the user of the chair may lock the extreme position of the top connecting link 52 shown in Fig. 2 by tightening the clamping screw 70. Now, after loosening the clamping screw 72, the user of the chair may start swinging movements of the back-rest, seat and leg-rest similar to that described above in connection with Fig. 1, with the only exception that the starting position of the members of the four-sided link-system is a different one. The dash and dot lines in Fig. 2 indicate one of the positions of the members of the four-sided link-system, which may be obtained by swinging the members of the four-sided link-system after tightening the clamping screw 70 and loosening the clamping screw 72. Of course, the dash and dot line position or any other intermediate position of the members of the four-sided link-system may be locked by tightening the clamping screw 72.

Instead of locking the extreme position of the top connecting link 52 shown in Fig. 2 after a swiveling movement of the locked four-sided link-system about the pivot 58, any intermediate position of the top connecting link 52 may be locked by tightening the clamping screw 70 as shown in Fig. 3. Starting from such a locked intermediate position of the four-sided link-system, the user of the chair may carry out swinging movements of the back-rest, seat and leg-rest after loosening the clamping screw 72. The dash and dot line position of the members of the four-sided link-system shown in Fig. 3 indicates one of the positions which may be obtained by such a swinging movement. It is understood that this or any other position obtained by a swinging movement of the members of the four-sided link-system may be locked by tightening the clamping screw 72.

In order to move the four-sided link-system from the full line position shown in Fig. 1 into the dash and dot line position shown in Fig. 2 for example, as a modification, first the clamping screw 72 could be loosened to permit a movement of the members of the four-sided link-system into the position shown in dash and dot lines in Fig. 1, whereupon after tightening the clamping screw 72 and loosening the clamping screw 70 the four-sided link-system may be swung about the pivot 58 into the dash and dot line position shown in Fig. 2, which, thereupon, may be locked by tightening the clamping screw 70.

Furthermore, if desired, both clamping means 70 and 72 could be loosened for changing the position of the members of the four-sided link-system from the full line position shown in Fig. 1 to the dash and dot line position shown in Fig. 2. Under these circumstances, the movement of the members of the four-sided link-system is composed of a movement of the top connecting link about its pivot 58 and a movement of the members 40, 42, 50, 52 relative to each other, said two movements taking place more or less at the same time.

In this connection, it may be mentioned, that clamping means such as the clamping screw 72 for locking an adjusted relative position of the members of the four-sided link-system and/or clamping means such as the clamping screw 70 for locking the position of the top connecting link 52 relative to the support may be entirely

omitted, if desired. If the clamping screw 72 is omitted, the members of the four-sided link-system may be held in any intermediate position by the above described balancing action of the user of the chair as long as the legs of the user of the chair are not in a level higher than the head of the user of the chair. If the clamping screw 70 is omitted, intermediate positions of the top connecting link cannot be locked, but the top connecting link is held in either one of its extreme positions by the stopping surface 34 and 36 respectively of the end of the leg 24.

In the embodiment of the reclining chair shown in Figs. 1-3 the clamping means 70 for locking the top connecting link 52 is coaxial with the pivot 58 between the top connecting link and the support. If desired, the clamping means for locking the top connecting link could be arranged at a place remote from the pivot 58. Furthermore, any other suitable type of clamping means could be used, if desired.

According to the embodiment of an adjustable reclining chair shown in Fig. 4, again one point of the four-sided link-system 140, 142, 150, 152 is in permanent operative engagement with the support 120, i. e. a point of the top connecting link 152 of said four-sided link-system is pivoted to said support 120 at 158. According to Fig. 4, however, the front connecting link 150 and the portion of the back-rest 140 between the pivots 144 and 156 are of equal length, and, likewise, the top connecting link 152 is of the same length as the seat 142, so that the four-sided link-system is in the shape of a parallelogram. The front connecting link 150 is rigidly connected with the leg-rest 146 swingably mounted on the seat 142 at 148. The arrangement of the clamping screws 170 and 172 is the same as that of the clamping screws 70 and 72 in the embodiment of the chair shown in Figs. 1-3. In order to limit the extreme sitting position of the members of the four-sided link-system 140, 142, 150, 152 of the chair shown in Fig. 4, an abutment 174 is arranged on the leg-rest 146 for engagement with the seat 142. If desired, said abutment could be arranged at any of the other corners of the four-sided link-system. Furthermore, such an abutment could be used in the chair shown in Figs. 1-3, if desired. The operation of the reclining chair shown in Fig. 4 is the same as the operation of the chair shown in Figs. 1-3.

The reclining chair shown in Fig. 6 is substantially the same as the reclining chair shown in Figs. 1-3. The four-sided link-system 240, 242, 250, 252 is swingably mounted on the support 220 at 258, and the front connecting link 250 is rigidly connected with the leg-rest 246 pivoted to the seat 242 at 248. The means for limiting the extreme positions of the top connecting link 252, however, are of different type. Stops 290 and 292 secured to the end 226 of the leg-rest 224 project inwardly therefrom and serve as an abutment for the top connecting link 252 in its extreme positions. As best shown in Fig. 8, the top connecting link 252 is pivoted to the support 220 by means of a pin 258 passing through registering holes in the end 226, the top connecting link 252 and a plate 294 of suitable shape secured to the end 226 by rivets 296. A clamping screw 270 screwed on the threaded end of the pin 258 serves to lock various positions of the top connecting link relative to the support 220. The locking device 272 arranged on the pivot 244 serves to lock an adjusted position of

the members of the four-sided link-system relative to each other. The operation of the chair shown in Fig. 6 is the same as the operation of the chair shown in Figs. 1-3.

Figs. 9-11 illustrate an office chair according to the invention. A spindle 301 carrying a supporting member 303 is screwed into the threaded bore of a pedestal 305, which may be of any conventional form. On each side of the chair an upright 307 is rigidly connected with said supporting member 303 by screws. A top connecting link 352 is swingably mounted on each upright 307 at 353. The rear end of each top connecting link 352 is pivoted to the back-rest 349 at 355. The lower end of the back-rest 349 is pivoted to the rear portion of the seat 342 at 344. The front portion of said seat 342 is pivotally connected at 348 with the lower end of the front connecting link 350, the upper end of which is pivoted at 354 to the front end of the top connecting link 352. A locking device 372 arranged on the pivot 344 may be used for locking the members of the four-sided link-system 340, 342, 350, 352 in an adjusted position relative to each other. Each upright 307 is provided with an abutment 334 and an abutment 336. The abutment 334 serves to limit the substantially horizontal position of the top connecting link 352, and the abutment 336 serves to limit the extreme reclined position of said top connecting link 352.

The abutment 334 is provided with an automatic latch mechanism generally indicated by 309. Said latch mechanism 309 comprises a hook-like member 311 swingably mounted in an aperture 313 of the abutment 334 at 315. A tension spring 317 stretched between the upper end of the hook 311 and the wall of the aperture 313 tends to urge the hook 311 into the vertical position in engagement with a stop 319 arranged in the aperture 313, as shown in full lines in Fig. 10. The upper end of the hook 311 may pass through a slot 321 at the lower wall of the top connecting link 352, and the hook itself may come into engagement with a portion of the lower wall of the top connecting link 352, when the latter is in the horizontal position shown in Fig. 10. If the hook 311 is engaged with the lower wall of the top connecting link 352, the latter will be held in its horizontal position. If it is desired to swing the top connecting link 352 about its pivot 353 into a reclined position, the hook 311 is brought by hand against the action of the spring 317 into the dash and dot line position 311', whereby the top connecting link 352 is released. After a swinging movement of the top connecting link 352 about the pivot 353 into a sufficiently reclined position, the hook 311 of the latch mechanism 309 may be released, whereupon the spring 317 returns the hook 311 into its vertical end position, the upper end of said hook now being below the lower wall of the top connecting link 352.

As best shown in Figs. 10 and 11, a torsion spring 323 surrounding the pivot 353 has its ends connected with the upright 307 and the top connecting link 352. When the user of the chair wishes to return from a reclined position into a sitting position, said torsion spring 323 will assist in such a change of the position by its tendency to urge the top connecting link into its horizontal end position limited by the abutment 334.

During the return of the top connecting link 352 into said horizontal position, the right hand

edge (as viewed in Fig. 10) of the slot 321 in the lower wall of the top connecting link 352 comes into engagement with the nose of the hook 311, whereby the latter is swung about its pivot 315 in counter-clockwise direction, until the upper end of the hook 311 may pass through the slot 321, whereupon the spring 317 automatically returns the hook 311 into its vertical position wherein the hook comes into engagement with the lower wall of the top connecting link 352 as shown in full lines in Fig. 10, thus locking the top connecting link in said horizontal end position.

When the top connecting link 352 is held in the horizontal position by the latch mechanism 309, the user of the chair may loosen the locking device 372 for adjusting the members of the four-sided link-system 340, 342, 350, 352 in a different position relative to each other if so desired. After such an adjustment of the members of the four-sided link-system, the members may be held in the thus adjusted position by a tightening of the locking device 372. Now, the chair may be used either in a stationary position of its movable members locked by the latch mechanism 309, or, after a release of the latch mechanism 309 and the top connecting link 352, as a swiveling chair, wherein the four-sided link system locked by the locking device 372 swings about the pivot 353 under or against the action of the torsion spring 323.

Furthermore, as best shown in Fig. 9, above described office chair has on each of its sides a separate arm-rest 325, the rear end of which is pivoted to the back-rest 349 at 327. The front end of each arm-rest 325 is pivoted at 329 to the upper end of a link 331, the lower end of which is pivoted to the top connecting link 352 at 333.

According to the embodiment of a chair shown in Fig. 12, the four-sided link-system 440, 442, 450, 452 is swingably mounted on the support 420 at 458. A locking device 470 may be used for locking the top connecting link 452 in a predetermined position relative to the support 420, and a locking device 472 may be used for locking the members of the four-sided link-system in a predetermined position relative to each other. As best shown in Fig. 14, the support 420 comprises two uprights 435 connected with each other by cross bars 437 and 439. The upper end of each upright 435 is provided with abutments 434 and 436 for cooperation with the top connecting link 452; said abutments 434, 436 serve to limit the extreme positions of the top connecting link. An adjustable stop screw 441 is threaded into a threaded bore of each of the abutments 436. Said stop screw 441 may be used for altering the extreme reclined position of the top connecting link 452, which may come into contact with the upper end of the stop screw 441, if the latter projects from the upper surface of the abutment 436.

Furthermore, a stop 443 is attached to the back-rest 440 by means of screws. Said stop 443 may abut against the top connecting link 452 for limiting the extreme reclined position of the members of the four-sided link-system as shown in dash and dot lines.

A leg-rest 446 swingably mounted on the front portion of the seat 442 at 445 at a point spaced from the pivotal connection 448 between the seat 442 and the front connecting link 450 has on each of its sides an extension 447 projecting beyond the pivotal connection 445 between the leg-rest 446 and the seat 442. According to Figs. 12 and 13, said extension 447 of the leg-rest 446 has an actuating projection 449 extending inwardly for

loose engagement with the front connecting link 450. Said actuating projection 449 may be held in engagement with the front connecting link 450 by means of a torsion spring (not shown) arranged between the seat 442 and the leg-rest 446. When, upon a tightening of the locking device 470 and a loosening of the locking device 472 the members of the four-sided link-system 440, 442, 450, 452 are brought into a different position relative to each other, for example into the reclined position shown in dash and dot lines in Fig. 12, the front connecting link 450 being in engagement with the actuating projection 449 of the extension 447 of the leg-rest 446 causes a swinging movement of the leg-rest 446 about its pivot 445, so that the leg-rest 446 reaches a different position relative to the seat 442.

A similar displacement of the leg-rest 446 relative to the seat 442 could also be obtained by a cooperation of the actuating means on the extension of the leg-rest with a portion or a projection of the top connecting link.

According to the embodiment of an adjustable reclining chair shown in Fig. 15, the four-sided link-system 540, 542, 550, 552 is swingably mounted at 558 on the support 520. Again, the locking device 572 may be used to hold the members of the four-sided link-system in an adjusted position.

As best shown in Figs. 15 and 19, a member 551 having a slot 553 is rigidly connected with the top connecting link 552, by welding, for example. A bolt 555 having a head 557 passes through the slot 553 of the member 551 and a bore 559 of the support 520. A protruding portion 561 arranged on the bolt 555 for engagement with a corresponding recess of the bore 559 prevents the bolt from rotation when a locking knob 563 screwed on the projecting threaded end of the bolt 555 is turned. When said locking knob 563 is tightened, the head 557 of the bolt 555 is pressed against the member 551 whereby said member and the top connecting link 552 rigidly connected therewith are locked in a predetermined position. When the locking knob 563 is loosened, the member 551 may be displaced relative to the head 557, so that the top connecting link 552 may be freely swung about its pivot 558. The extreme positions of the top connecting link 552 are limited by an engagement of the ends of the slot 553 with the bolt 555.

A leg-rest 546 is swingably mounted on the front portion of the seat 542 at a point 545 spaced from the pivotal connection 548 between the front connecting link 550 and the seat 542. Said leg-rest 546 has an extension 547 for a purpose to be described hereinafter.

As best shown in Figs. 15-17, the front connecting link 550 is provided with a series of openings 565. Each opening is composed of a cylindrical bore 567 and lateral recesses 569. An actuating member generally indicated by 571 may be inserted into one of said openings 565. As best shown in Fig. 18, said actuating member 571 has a cylindrical main body 573 and a cylindrical engaging portion 575 of reduced diameter. Said cylindrical engaging portion 575 is provided with extensions 577 at diametrically opposite sides. The engaging portion 575 may be inserted into one of the openings 565, the shape of the extensions 577 being such as to pass through the recesses 569 of such an opening 565. When the engaging portion 575 of the actuating member 571 is inserted into one of said openings 565 until the shoulder 579 of the main body 573 abuts against the surface of the front con-

necting link 550 as shown in Fig. 17, the actuating member 571 may be rotated through an angle of 90° until the extensions 577 reach the vertical position shown in Fig. 17, whereby the actuating member 571 is locked in its position on the front connecting link 550.

Now, assume the leg-rest 546 is in the idle position shown in Fig. 15. When the user of the chair wishes to use the leg-rest, at first the actuating member 571 is removed from an opening 565 of the front connecting link 550. Thereupon, the extension 547 of the leg-rest may be gripped by hand for swinging the leg-rest 546 about its pivot 545 into an inclined position, for example the position 546' with the extension 547 of the leg-rest beyond an opening 565 of the front connecting link selected for receiving the actuating member 571. Thereupon, the actuating member 571 may be inserted into said opening 565, for example into the uppermost opening as shown in Figs. 15-17. Now, when the leg-rest 546 is released, the extension 547 of the leg-rest will be held in loose engagement with the actuating member 571 by the action of the weight of the leg-rest 546. It will be readily understood, that the position 546' of the leg-rest will be changed relative to the seat 542 in a similar manner as described above in connection with the leg-rest 446 shown in Fig. 12, when the members of the four-sided link-system 540, 542, 550, 552 are adjusted in a different position.

If the user of the chair wishes to have a different initial position of the leg-rest 546 relative to the seat 542, he may insert the actuating member 571 into a different opening of the series of openings 565. For example, if the actuating member 571 is inserted into the lowermost opening 565, the leg-rest may be brought into the position 546''.

According to the embodiment of a chair shown in Figs. 20-23, the top connecting link 652 of the four-sided link-system 640, 642, 650, 652 is swingably mounted on the support 620 at 658. A rod 681 bent to form a semi-circle carrying stops 683 and 685 is rigidly connected with the top connecting link 652, by welding, for example. As best shown in Fig. 22, the rod 681 is in engagement with an aperture 687 of a ring-like end portion 689 of a bolt 691 passing through a bore 693 of the support 620. When a locking knob 695 screwed on the threaded end of the bolt 691 is tightened, the rod 681 is tightly pressed against the surface of the support 620 by means of the ring-like end portion 689 of the bolt 691, so that the rod 681 as well as the top connecting link 652 are locked in their position. When the locking knob 695 is loosened, the rod 681 may slide in the aperture 687 of the end portion 689 of the bolt 691, so that the top connecting link 652 may be freely swung about its pivot 658. The extreme positions of the top connecting link 652 are limited by an abutment of the stop 683 or the stop 685 against an edge of the support 620.

A leg-rest 646 swingably mounted on the seat 642 at 645 has an upward extension 647. One end of a connecting bar 697 is pivoted to said extension 647 at 699. Said connecting bar 697 has a slot 602 capable of receiving a bolt 604 inserted with its square portion 606 into a corresponding square aperture of the front connecting link 650, as shown in Fig. 21. Said square portion 606 prevents the bolt 604 from rotation when a locking knob 608 screwed on the threaded

end of the bolt 604 is turned. When said locking knob 608 is tightened, the head 610 of the bolt 604 and the connecting bar 697 are pressed against the surfaces of the front connecting link 650, so that the latter as well as the leg-rest 646 connected with said connecting bar are held in their position. Such a tightening of the locking knob 608 causes also a locking of all members of the four-sided link-system 640, 642, 650, 652 in their adjusted position, so that it is unnecessary to arrange any additional locking device, for example on the pivotal connection 644 between the back-rest 640 and the seat 642.

When the locking knob 608 is loosened, the slot 602 of the connecting bar 697 may freely slide along the bolt 604, so that the leg-rest 646 may be brought into a different position, for example into the extreme position 646 shown in dash and dot lines in Fig. 20. Now, if the locking knob 608 is tightened again, so as to hold the leg-rest in said position 646 relative to the seat 642 and furthermore to hold the members of the four-sided link-system in their adjusted position relative to each other, for example the position shown in full lines in Fig. 20, the locking knob 695 may be loosened, whereupon the members of the four-sided link-system 640, 642, 650, 652 may be swung about the pivot 658 into the extreme reclined position shown in Fig. 23, which is limited by an abutment of the stop 685 against the support 620. The members of the chair may be held in said position by a tightening of the locking knob 695.

Of course, the right-hand end (as viewed in Fig. 20) of the connecting bar 697 could be pivotally connected with the front connecting link 650 and the left-hand end could be in shiftable engagement with a bolt on the extension of the leg-rest, if desired; in such a case, the locking knob 608 could be arranged on the bolt inserted into a hole of the extension of the leg-rest.

While I have shown only chairs, I do not wish that the invention be limited to chairs only. The invention may also be applied to other articles of furniture, such as couches or the like.

Furthermore, it is understood, that certain parts, elements, or mechanisms shown in a certain figure may be substituted for corresponding parts, elements, or mechanisms of the embodiments shown in other figures of the drawings.

I have described preferred embodiments of my invention, but it is understood that this disclosure is for the purpose of illustration, and that various omissions or changes in shape, proportion, and arrangement of parts, as well as the substitution of equivalent elements for those herein shown and described, may be made without departing from the spirit and scope of the invention as set forth in the appended claims.

What I claim is:

1. A reclining article of furniture comprising: a support, a seat, a back-rest, said back-rest being pivoted to the rear portion of said seat, a pair of connecting links on each side of the chair, substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link-system the sides

of which being adjustable with respect to each other, only one point of said four-sided link system being in permanent operative engagement with said support, said point being formed by a pivotal connection of said top connecting link with said support for varying the relative position between the four-sided link system and the support, first locking means associated with the top connecting link and said support for locking the top connecting link in an adjusted position, and second locking means acting on the relatively movable members of the four-sided link system for locking the sides of the link-system in an adjusted position relative to each other.

2. A reclining article of furniture as claimed in claim 1, said four-sided link-system being in the shape of a parallelogram.

3. A reclining article of furniture as claimed in claim 1, said four-sided link-system having sides of unequal length.

4. A reclining article of furniture as claimed in claim 1, said pivotal connection between the top connecting link and the support being substantially in the center of said top connecting link.

5. A reclining article of furniture comprising: a support, a seat, a back-rest, said back-rest being pivoted to the rear portion of said seat, a pair of connecting links on each side of the chair substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link-system the sides of which being adjustable with respect to each other, only one point of said four-sided link-system being in permanent operative engagement with said support, said point being formed by a pivotal connection of said top connecting link with said support for varying the relative position between the four-sided link-system and the support, means on the support for limiting the extreme positions of the top connecting link, first locking means associated with the top connecting link and said support for locking the top connecting link in an adjusted position, and second locking means acting on the relatively movable members of the four-sided link-system for locking the sides of the link-system in an adjusted position relative to each other.

6. A reclining article of furniture comprising: a support, a seat, a back-rest, said back-rest being pivoted to the rear portion of said seat, a pair of connecting links on each side of the chair substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link system the sides of which being adjustable with respect to each other, only one point of said four-sided link-system being in permanent operative engagement with said

7. A reclining article of furniture comprising: a support, a seat, a back-rest, said back-rest being pivoted to the rear portion of said seat, a pair of connecting links on each side of the chair substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link system the sides of which being adjustable with respect to each other, only one point of said four-sided link-system being in permanent operative engagement with said

support, said point being formed by a pivotal connection of said top connecting link with said support for varying the relative position between the four-sided link-system and the support, means on the support for limiting the extreme positions of the top connecting link, means cooperating with the four-sided link-system for limiting the extreme relative positions of the sides thereof in one direction, first locking means associated with the top connecting link for locking an adjusted position of the top connecting link, and second locking means associated with the four-sided link-system for locking an adjusted position of the sides of the four-sided link system relative to each other.

7. A reclining article of furniture comprising: a support, a seat, a back-rest, said back-rest being pivoted to the rear portion of said seat, a pair of connecting links on each side of the chair substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link-system the sides of which being adjustable with respect to each other, only one point of said four-sided link-system being in permanent operative engagement with said support, said point being formed by a pivotal connection of said top connecting link with said support for varying the relative position between the four-sided link-system and the support, first locking means associated with the top connecting link for locking an adjusted position of the top connecting link, second locking means associated with the four-sided link-system for locking an adjusted position of the sides of the four-sided link-system relative to each other, and a leg-rest swingably mounted on the front portion of said seat, at least one of said connecting links being in operative engagement with said leg-rest.

8. A reclining article of furniture comprising: a support, a seat, a back-rest, said back-rest being pivoted to the rear portion of said seat, a pair of connecting links on each side of the chair substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link-system the sides of which being adjustable with respect to each other, only one point of said four-sided link-system being in permanent operative engagement with said support, said point being formed by a pivotal connection of said top connecting link with said support for varying the relative position between the four-sided link-system and the support, means on the support for limiting the extreme positions of the top connecting link, first locking means associated with the top connecting link,

link for locking an adjusted position of the top connecting link, second locking means associated with the four-sided link-system for locking an adjusted position of the sides of the four-sided link-system relative to each other, and a leg-rest swingably mounted on the front portion of said seat, at least one of said connecting links being in operative engagement with said leg-rest.

9. A reclining article of furniture comprising: a support, a seat, a back-rest, said back-rest being pivoted to the rear portion of said seat, a pair of connecting links on each side of the chair, substantially above the plane of the seat, each pair of connecting links including a top connecting link and a front connecting link, adjacent ends of such top and front connecting links being pivotally connected with each other, the rear end of each top connecting link being pivoted to an intermediate point of the back-rest above the pivotal connection between the back-rest and the seat, the lower end of each front connecting link being pivoted to the front portion of the seat, said seat, said back-rest and said pair of connecting links forming a four-sided link-system the sides of which being adjustable with respect to each other, only one point of said four-sided link-system being in permanent operative engagement with said support, said point being formed by a pivotal connection of said top connecting link with said support for varying the relative position between the four-sided link-system and the support, means on the support for limiting the extreme positions of the connecting link, means cooperating with the four-sided link-system for limiting the extreme relative positions of the sides thereof in one direction, first locking means associated with the top connecting link for locking an adjusted position of the top connecting link, second locking means associated with the four-sided link-system for locking an adjusted position of the sides of the four-sided link-system relative to each other, and a leg-rest swingably mounted on the front portion of said seat, at least one of said connecting links being in operative engagement with said leg-rest.

10. In a reclining article of furniture as claimed in claim 1, resilient means arranged between the support and the top connecting link for returning the latter from a reclined position into the sitting position.

11. In a reclining article of furniture as claimed in claim 7, resilient means arranged between the support and the top connecting link for returning the latter from a reclined position into the sitting position.

12. In a reclining article of furniture as claimed in claim 1, an automatic latch mechanism associated with said top connecting link for holding same automatically in extreme positions.

13. In a reclining article of furniture as claimed in claim 7, an automatic latch mechanism associated with said top connecting link for holding same automatically in extreme positions.

14. In a reclining article of furniture as claimed in claim 7, said connecting link being rigidly connected with said leg-rest.

15. In a reclining article of furniture as claimed in claim 7, said operative engagement between said connecting link and said leg-rest including abutting surfaces on said two last mentioned members loosely engaged with each other.

16. In a reclining article of furniture as claimed in claim 7, said operative engagement

between said connecting link and said leg-rest including a link arranged between and pivotally connected at its ends with said two last mentioned members.

17. In a reclining article of furniture as claimed in claim 7, said operative engagement between the leg-rest and at least one of the connecting links including the front connecting link, and cooperating abutting surfaces arranged on said leg-rest and said front connecting link, 10 said cooperating abutting surfaces being loosely engaged with each other.

18. In a reclining article of furniture as claimed in claim 7, said operative engagement between the leg-rest and at least one of the connecting links including the front connecting link, 15 an abutting element adjustably mounted on said front connecting link, said abutting element being loosely engaged with the leg-rest.

ANTON LORENZ. 20
